Primary Examiner — T Chase Nelson(74) *Attorney, Agent, or Firm* — Banner & Witcoff, Ltd.(57) **CLAIM**

The ornamental design for a shoe outsole, as shown and described.

DESCRIPTION

FIG. 1 is a front perspective view of a shoe outsole showing our new design;

FIG. 2 is a bottom view thereof;

FIG. 3 is a rear perspective view thereof;

FIG. 4 is an enlarged view of FIG. 1 with environmental portions removed for clarity;

FIG. 5 is an enlarged view of FIG. 2 with environmental portions removed for clarity; and,

FIG. 6 is an enlarged view of FIG. 3 with environmental portions removed for clarity.

The broken lines immediately surrounding the photographic area define the bounds of the claimed design and form no part thereof. The broken lines showing the remainder of the shoe represent unclaimed subject matter and form no part of the claimed design.

1 Claim, 6 Drawing Sheets(56)
